CLAIM

The ornamental design for multi-axis linkage casting deburring equipment (CNC) as shown and described.

DESCRIPTION

The file of this patent contains at least one drawing/photograph executed in color. Copies of this patent with color drawing(s)/photograph(s) will be provided by the Office upon request and payment of the necessary fee.

1. Multi-axis linkage casting deburring equipment (CNC)

1.1: Front

1.2: Back

1.3: Left

1.4: Right

1.5: Top

1.6: Bottom

1.7: Perspective

(Continued)

The broken lines depict portions of the multi-axis linkage casting deburring equipment (CNC) that form no part of the claimed design.

1 Claim, 7 Drawing Sheets
